CLAIM

The ornamental design for a housing for electronic components, as shown and described.

DESCRIPTION

FIG. 1 is a perspective view of the housing for electronic components;

FIG. 2 is a front view thereof;

FIG. 3 is a right side view thereof;

FIG. 4 is a left side view thereof; and,

FIG. 5 is a top view thereof.

The rear of the housing forms no part of the claimed design.

The bottom of the housing forms no part of the claimed design.

The broken line illustrations of control buttons are not part of the design to be patented.
